PULLEY

Filed Aug. 30, 1928

INVENTOR:
AUGUST J. CHATTILLION.
By Harry A. Barnes
ATTORNEY.

UNITED STATES PATENT OFFICE

AUGUST J. CHATTILLION, OF ST. LOUIS, MISSOURI, ASSIGNOR OF ONE-HALF TO HARRY BUEHLER, JR., OF ST. LOUIS, MISSOURI

PULLEY

Application filed August 30, 1928. Serial No. 302,932.

My invention has relation to improvements in pulleys and consists in the novel features of construction more fully set forth in the specification and pointed out in the claim.

5 The invention is directed more particularly to pulleys having a fiber rim secured to a wrought steel or equivalent spider, and briefly, it consists in a rim formed out of layers of a suitable fiber, such as paper or leather, said 10 layers, being closely compressed and held together by suitable dowels. The dowels, at the same time, serve to secure the rim to the spider which is preferably formed of band steel. The fiber sheets are built up in such a 15 way as to present the ends of the sheets to that surface which forms the face of the pulley, so as to obtain the benefit of the greater friction resulting therefrom.

The principal object of the invention is to 20 provide a pulley with a fiber rim in combination with a steel spider so as to obtain the benefit of the fiber rim without unduly increasing the weight of the pulley, and, at the same time, to provide a pulley that has the 25 necessary strength and simplicity of construction. Further and other advantages, such as comparatively low cost of manufacture, will be better apparent from a detailed description of the invention in connection with the 30 accompanying drawings in which—

Figure 1 is a side elevation of my improved pulley with parts broken away to show one of the hub members in section; Fig. 2 is a vertical transverse section taken on the line 2—2 35 of Fig. 1; Fig. 3 is a horizontal cross section taken on the line 3—3 of Fig. 1; Fig. 4 is a side elevation of a modified construction of pulley, wherein a disc or web replaces the spider; Fig. 5 is a fragment of the pulley of 40 modified construction showing the spoke arrangement used in wide-faced pulleys; and Fig. 6 is a vertical cross section taken on the line of 6—6 of Fig. 5.

Referring to the drawings, 1 represents the 45 rim of a pulley P, said rim being turned out of, or otherwise formed from a block built up of a plurality of fiber laminations a, which are very greatly compressed so as to form a homogeneous block. The pulley P is 50 preferably made in sections S, S joined along

the line x. The rim 1 may be provided with a medial slot 2, extending inwardly from the inner surface of the rim to a substantial depth, and a metallic ring section 3 is then inserted in the slot 2 of each section. A plurality of holes are bored through the pulley rim 1 and ring 3 for the reception of dowel pins 4 which hold the laminations a together as well as the ring 3 in place, virtually forming these members into an integral structure. 55 Of course, the laminations are also glued to one another prior to their being compressed. The pulley hub H comprises sections 5, 5, 60 each of which are bent into proper semi-cylindrical shape from a suitable steel plate, and a series of spokes 6 connect each hub section with the corresponding rim section. Each of the spokes may be formed of oppositely disposed spoke members m, m, which 65 members are riveted at their outer ends to opposite sides of the ring 3 and have outwardly turned flanges m', m' at their inner ends, which flanges are riveted to a hub section 5. Along the line x on which the sections S, S are joined, a pair of complementary loop members 7 and 8 are affixed to the 70 ring sections 3, 3, the members 7 being provided with an outwardly projecting lug 9 adapted to enter a recess 10 formed in the member 8. A bolt 11 is then passed through 75 the loop members 7 and 8 and a nut screwed on the projecting end of the bolt for the purpose of securely fastening the sections together. The purpose of the interlocking 80 formations 9 and 10 is to prevent the displacement of one section relative to the other with its resulting irregularity of pulley surface. The pulleys are, of course, locked together in the manner just described at opposite points as shown in the drawings. 85

It is also necessary to secure the hub sections together, and suitable brackets 13, 13 are provided for this purpose. The brackets are identical and each of them are provided with outwardly projecting perforated portions 14 connected by a circular portion 15, the latter being concentric with the hub section. In order to give the brackets rigidity they are U-shaped in cross section as shown in Fig. 3. Each bracket 13 is secured by a 90 95 100

short pin 16 to a cylindrical member 17 between which and the bracket is a spacer 17'. The member 17 in turn is riveted to the adjacent hub section 5. After having mounted 5 a pulley on a shaft (not shown) the hub sections are tightly clamped together by the means of bolts 18 passed through the brackets 13 which are drawn tightly together by nuts 19 screwed over the bolts. The shape of 10 the brackets 13 is such that they will stand considerable pressure without becoming distorted.

In order to finish the side faces f, f' of 15 the pulley a metallic ring 20 may be placed on each side of the fiber laminations a , said rings being held in place by large head screws 21 (as shown in Fig. 3) or any equivalent device.

In the manufacture of comparatively small 20 pulleys the hub and rim may be connected by a disc or web 22 as shown in Fig. 4. This may be formed either in sections or integral as desired.

In applying the invention to pulleys having 25 exceptionally wide faces a series of spokes 23 will be employed so as to support the pulley throughout the entire width of the face, and these spokes will preferably lie in different planes, or will alternate as shown in 30 Figs. 5 and 6.

Having described my invention, I claim:

A pulley comprising a pair of complementary sections, each section comprising 35 rim and hub elements, and spokes connecting said elements, said rim elements including fiber laminations and a metallic ring embedded therein, each spoke comprising a pair of spoke members, the members of each pair being connected to opposite sides of said ring 40 and diverging toward the hub, means for connecting the pulley sections at the rim, and means for connecting the sections at the hub, the last mentioned means being fixed to the hub elements between the spoke members.

45 In testimony whereof I heretunto affix my signature.

AUGUST J. CHATTELLION.
